UNITED STATES PATENT OFFICE.

ROSWELL T. SMITH, OF NASHUA, NEW HAMPSHIRE.

AUTOMATIC STITCH-ADJUSTING MECHANISM FOR EMBROIDERING-MACHINES.

SPECIFICATION forming part of Letters Patent No. 377,410, dated February 7, 1888.

Application filed March 25, 1887. Serial No. 232,375. (No model.)

To all whom it may concern:

Be it known that I, ROSWELL T. SMITH, a citizen of the United States, residing at Nashua, in the county of Hillsborough and State of New Hampshire, have invented new and useful Improvements in Automatic Stitch-Adjusting Mechanism for Embroidering-Machines, of which the following is a specification.

My present invention relates to embroidery-machines of the type generally known as the "Heilmann" or "Swiss" machines, wherein the several stitch adjustments are effected by a pantograph mechanism, the tracing-point thereof being carried over the pattern by the hand of the operator, who also operates the needle-carriages, locks and unlocks the needles, and controls every mechanical function. Since the first introduction of these machines various means have been devised for rendering them in part automatic. For example, it has been proposed to effect the reversal of the "railway" by means of the devices which regulate the thread-tension, and in applications for Letters Patent filed by me upon the 10th day of June, 1885, and the 9th day of July, 1886, and numbered in serial 168,237 and 207,609, respectively, I have shown, described, and claimed mechanism for accomplishing this purpose by the make and break of an electric circuit. Prior, however, to the date of the invention contained in the earlier of these applications there has never been, so far as I am aware, any instance in which an embroidery-machine of this type has been rendered entirely automatic. In both the applications referred to I have shown and described mechanism organized to accomplish this result, in which the minor as well as the more important functions are effected by devices which are wholly automatic in action. In other words, the reversal of the railway, the transfer of the needles from one carriage to the other, and the successive stitch adjustments of the tambour-frame are all carried out by mechanical means without the intervention of any human agency.

It is the purpose of my present invention to provide an improved automatic mechanism for giving the proper stitch adjustment to the tambour-frame, and for rendering said adjustment exact and accurate to a high degree, whereby the character of the work produced

is greatly promoted, a uniform excellence of finish secured throughout, and the machine made capable of performing a grade of work not heretofore attainable.

My invention also contemplates improved means for imparting motion to the pattern, which will be termed the "stencil-sheet" throughout this specification, the purpose of such improvement being to establish a synchronous relation between the forward movement of said stencil and the action of any one or more of the mechanical elements by which the stitch adjustment is effected.

It is an important feature of the invention, also, to provide positive means for initiating the progressive movement of the stencil at the moment when the needle-carriage begins to recede from the web, in order that the movement of the tambour-frame may take place during the period when the needles are disengaged from the fabric.

My invention also comprises important improvements in the construction and combination of the mechanical elements by which the stitch adjustments are made, whereby great exactness is secured, and whereby, also, a simultaneous operation of the actuating-levers in opposite directions is rendered impossible. The main feature or most important part of the present invention, however, consists in the positive means whereby the movement of the tambour-frame is directed and the extent of its adjustment controlled. It is by the intervention of this element in the combination that the embroidery mechanism is rendered practically and entirely automatic.

The invention consists in the several novel features of construction and combinations of parts, hereinafter fully set forth, and definitely pointed out in the claims annexed to this specification.

Referring to the drawings forming part of this application, Figure 1 is a view in elevation of a mechanism embodying my invention, the line of sight being parallel with the railway of the embroidery-machine. Fig. 1^a is a diagram illustrating the action of the device by which the progressive movement of the stencil is initiated. Fig. 2 is an elevation taken from the right hand of Fig. 1, the line of sight being at right angles with the railway. Fig. 3 is a detail section in the line x x, Fig.

1, certain points being omitted. Fig. 4 is a detail elevation, on an enlarged scale, of part of the mechanism shown in Fig. 1. Fig. 5 is a partial elevation of the lower portion of Fig. 5 1, taken from the opposite side. Fig. 6 is a detail section taken in the plane $y-y$, Fig. 5. Fig. 7 is a detail perspective of part of the devices for initiating the movement of the stencil. Fig. 8 is a detail elevation of the stencil-drum detached. Figs. 9 and 9^a are plan views 10 of part of a stencil-sheet.

It is my intention to connect the mechanism forming the subject-matter of the present invention to any pattern of embroidering-machine, the preferred type being that in which the reversal of the railway is effected by the pneumatic apparatus, which forms the subject of a separate application filed by me and pending concurrently herewith, the same being 20 numbered in serial 232,552. Inasmuch, however, as I may use the reversing mechanism shown in my former application, filed July 9, 1886, with equally good results, and for the reason that the present invention may be applied to any form of machine without material 25 change, I have shown in this case so much only of the embroidering mechanism as is needed to clearly establish the connection between the operative parts.

30 In the said drawings, the reference-numeral 1 designates one side of the railway of any suitable type of embroidering-machine, upon which a needle-carriage moves upon each side of the web, one end of one of said carriages 35 being represented at 2, said carriage being drawn toward the tambour-frame by weights in the usual manner, while its retrograde movement is produced by a belt, 3, moving in a slotted projection, 4, on each end of the carriage, and having a driving-block rigid on said belt, in the manner shown in my application filed July 9, 1886, Serial No. 207,609. Upon the central portion of the railway is a standard, 5, forming part of a rectangular 40 frame within which the tambour-frame is suspended. I have indicated the presence of these parts by dotted lines, inasmuch as they form no part of the present invention and may or may not be of novel construction and 45 arrangement themselves. The tambour-frame referred to is moved to give the required stitch adjustments by a pantograph mechanism of substantially the same construction as that heretofore employed in machines of the 50 Swiss type and others.

Upon one side of the machine and about opposite the structure supporting the tambour-frame I erect a standard, 6, upon which the operative parts of the mechanism embodying 60 my invention are supported. Projecting from the upper portion of this standard toward the end of the tambour-frame is a bracket, 7, of cruciform shape, upon which are arranged a horizontal and a vertical slide-bar, (denoted by 65 the numerals 8 and 9, respectively.) Of these slide-bars the former is mounted in bearings 10 on the ends of the long arm of the bracket,

while the vertical slide is carried in similar bearings, 11, on the cross-arm. In both cases sufficient frictional contact is insured to retain 70 either part in any position to which it may be adjusted. The bearings 11 are projected forward far enough to bring the vertical slide in front of the horizontal with sufficient intermediate space to admit the parts carried by 75 said bars, as shown in Figs. 2 and 3.

Upon the horizontal bar 8 is rigidly mounted a cross-arm, 12, having a true vertical position and provided with a slot, 13, extending nearly from end to end of the arm. Upon the 80 vertical arm 9 is mounted, in a similar manner, a cross-arm, 14, having a true horizontal arrangement and provided with a slot, 15, which is coextensive with that in the arm 12. These arms are mounted upon the inner or adjacent 85 faces of the slide-bars carrying them, and when in their normal position they cross each other centrally at right angles, as shown in Fig. 1. In the space intervening between the adjacent faces of these cross-arms is introduced the extremity 16 of the motor-arm of the pantograph. Mounted in the end of this arm is a pin, 17, projecting on both sides of the arm and having one end lying in the slot 13 and the other end in the slot 15 of the vertical and horizontal cross-arms, respectively. 90 This pin corresponds to the tracing-point of the pantograph, which is usually held in the hand of the operator and made to traverse the 95 pattern.

It will readily be seen that by adjusting the vertical and horizontal slide-bars 8 and 9, one or both, the pantograph may be actuated and movement in any direction imparted to the tambour-frame, the extent of such adjustment 105 being exactly proportional to the degree of movement imparted to the slide-bars. For example, a longitudinal movement of the bar 9 will carry the arm 16 vertically in either direction, the pin 17 moving in the slot 13 of the cross-arm 12, while in the same manner a movement of the horizontal bar 8 will give similar adjustment to the pantograph-arm, its pin sliding in the slot 15. This arrangement is made clear in Fig. 3, and it will be apparent that when circumstances require it the vertical and horizontal adjustment may take place simultaneously, in which case the line of movement will be the diagonal resultant of the combined vertical and horizontal adjustment. 115

Upon the edges of each of the slide-bars 8 and 9 are formed or mounted oppositely-toothed racks 18 and 19, the pitch of the teeth of the former being such as to give motion in one direction by the reciprocation of an engaging spring-actuated pawl, while the teeth of the rack 19 upon the opposite edge have the opposite pitch. The length of these racks is commensurate with the extent of movement required for the adjustments of the tambour-frame, and they may be formed at any convenient part of the slide-bars or upon attachments to said bars. 125 130

Above and below the horizontal slide-bar 8 are mounted bell-crank levers 20, so arranged that the extremities of their vertical arms approach the toothed edges of the bar. Upon 5 the upper bell-crank is pivoted a pawl, 21, normally engaged with the rack 18 by the tension of a spring, 22. A similar pawl, 23, is carried by the lower bell-crank, its nose being turned in the direction opposite to that of 10 the pawl 21 to engage with the rack 19, having teeth of opposite pitch. Each bell-crank is acted upon by a spring, 24, connected to its horizontal arm, by which the lever is swung back after each forward movement of the pawl 15 carried by it.

Upon a bracket, 25, projecting past the lower end of the vertical arm 9, are mounted two levers, 26 and 27, the former being a simple lever of the first order, and the latter a 20 compound lever composed of the two parts 27^a and 27^b, connected by a joint, 28. Upon the extremities of these levers are pivotally mounted pawls 29 and 30, by which a downward and an upward adjustment may be given, 25 respectively, to the slide-bar 9. These pawls are drawn into engagement with the opposite racks 18 and 19 by springs 31, and to the power end of each lever is connected a spring, 32, by which their opposite extremities are 30 retracted after each reciprocation of the pawl. The power ends of these levers project beyond the standard 6 and are curved to bring them into different vertical planes, and a similar construction is applied to the horizontal arms of the bell-crank levers 20, all 35 four projecting extremities being arranged in substantially the same vertical plane when viewed from the point of sight in Fig. 1, but in different vertical planes when viewed from 40 a point removed ninety degrees from that in Fig. 1, as shown in Fig. 2.

Upon the standard 6, beneath the power ends of the levers described, are mounted brackets 45 33, within which are supported five vertical bars or rods, each capable of independent vertical movement in the bracket 33. Of these four are motor-bars, and are designated by the letters a', a², a³, and a⁴, the two first being arranged to abut against the power ends of the 50 levers 26 and 27, and the two latter engaging with the horizontal arms of the bell-cranks 20, as shown in Figs. 1 and 2. The fifth rod, 34, has a wholly distinct function, which will presently be described. The two longer bars, a³ 55 and a⁴, receive support from a third bracket, 35, a free movement being at the same time permitted in either direction. By the repeated reciprocation of the lettered bars the levers operating the slide-bars 8 and 9 are actuated, 60 and movement in corresponding directions is given to the motor-arm 16 of the pantograph.

Upon the lower portion of each of the five bars is a stud or tooth, 36, which rests on the lower bracket 33 and supports the bars when 65 not in action, and upon these studs rests a rod, 37, carried by an arm, 38, pivoted upon the standard 6 in rear of the motor-bars. To the

arm 38 is pivotally connected a link, 39, connected at its lower extremity to a latch, 40. It will be seen that by the rise of any one of 70 the five bars the arm 38 will be lifted and communicate a like movement to the latch 40.

Projecting from the standard 6 toward the railway 1 is a bracket, 41, upon the end of which is pivotally mounted a platform, 42, the 75 forward extremity of which rests upon a shaft, 43, having an eccentric, 44, by the rotation of which a reciprocating movement is imparted to the platform, which rocks upon its pivotal point 45. Upon the outer end of the platform 80 42 are mounted on pivotal supports five independent selectors, 46, arranged beneath the ends of the bars 34 a', a², &c. The ends of the bars and of these selectors are so formed that by a forward rocking movement of any one of 85 the selectors an engagement is made by which the motor-bars engaged is raised as the platform 42 rises. These selectors 46 are each thrown forward normally and brought under the motor-bars by springs 47, and from the lower 90 bracket 33 depends a yoke, 48, which lies in front of the selectors and beneath forwardly-projecting lugs 49 mounted thereon. As the the platform 42 falls, these lugs engage at or near the lowest point of vibration with the 95 yoke and draw all the selectors back, thereby breaking the engagement of any one or more of them with the motor-bars.

Upon the forward end of the platform 42 are arms 50, between which is rigidly mounted a 100 drum, 51, having its peripheral surface in front of and in convenient proximity to the selectors 46. This drum is constructed in two parts or sections, between which lies a disk, 52, of equal diameter, having peripheral teeth 53 at 105 suitable intervals. This disk is keyed to a shaft, 54, journaled in arms 50 and supporting the drum sections, as seen in Fig. 6, and upon one end of said shaft is a ratchet, 55, rigidly mounted. The end of the shaft projects beyond the ratchet 55 and carries a vibrating arm, 56, upon one end of which is mounted a pawl, 57, drawn by a spring, 58, into operative engagement with the teeth of the ratchet. Upon the same side of the pivotal axis of said 110 bar is swiveled a sleeve, 59, through which projects a pitman, 60, which receives reciprocation from a wrist-pin on a disk, 61, carried by the shaft 43. Upon this pitman is mounted an adjustable boss, 62, which at each reciprocation of the pitman will impinge upon the end of the sleeve 59, and, provided the end of the arm 56 is retracted sufficiently, will vibrate said arm and throw the pawl far enough to turn the ratchet 55 one or more teeth. Unless, 115 however, this retraction of the pawl-carrying end of the vibrating arm 56 takes place, the pitman 60 will simply reciprocate in the swiveling sleeve 59 without effect upon the ratchet. The inner end of the vibrating arm 56 projects 120 beyond the periphery of the drum 51 and carries a horizontal pad, 63, which projects inward over the end of the latch 40. It will be now seen that when the bar 34 or any one

or more of the lettered motor-bars a' a'' , &c., rise, the latch 40 will be lifted, the vibrating arm 56 will retract the pawl 57, and the pitman 60 will immediately advance the ratchet 55, thereby turning the shaft 54 and the toothed disk 52 keyed thereon. This action will be repeated as often as any one of the five vertical bars is operated by its selector 46.

Over the drum 51 is carried the stencil-sheet 64, by which the action of the motor-bars and consequently the movements of the motor-arm of the pantograph are directed and controlled. This stencil consists of a narrow sheet of any suitable material, thin brass being preferable. In this sheet is formed a central series of perforations, 65, which engage with the teeth 53 of the disk 52. Upon each side of this line are formed two separate series of openings, b' , b'' , b^3 , and b^4 , corresponding in transverse arrangement with the position of the selectors 46. Upon each of these selectors is pivoted a finger, 66, supported and guided by a bracket-plate, 67, mounted on the platform. These fingers are of such length that when the selectors are thrown back their points will lie just a little withdrawn from the surface of the stencil-sheet as it lies upon the drum 51. In the latter are formed openings 68, so situated that the ends or points of said fingers may enter the same after passing through the openings b' b'' , &c., in the stencil. As the platform 42 rises, lifting the lugs 49 of the selectors off the yoke 48, the selectors will rock toward the drum and the finger-points 66 will rest upon such portions of the stencil-sheet as happen to be imperforate at the point of contact. In this event the engagement between the selector and the motor-bar will be impossible. Should, however, any one of the openings b' b'' , &c., present themselves to the finger-points, this engagement will be effected and will be repeated as long as the stencil-opening continues to present itself to the finger.

Within one section of the drum 51 is arranged a sleeve, 69, loose upon the shaft 54, and having an arm, 70, which projects through a peripheral opening in the drum-section and carries an angular boss, 71, upon its end, lying partly in the opening in the drum, but having its end projecting beyond the end of the drum. In a cavity in the end of the sleeve 69 is a spring, 72, bearing against the disk 52 and giving sufficient frictional contact to prevent backlash or displacement of the feeding-disk 52, while at the same time it holds the arm 70 in any position given it. The opening 73 in the drum, in which the boss 71 lies, is of such length as to permit said boss to rise a short distance; but when in its normal position, as in Fig. 1, it lies directly in front of the finger 66, mounted on the selector, which lies beneath and operates the bar 34. As explained hereinafter, the organization of parts is such that the stencil-sheet, which is provided with a transverse imperforate portion between each transverse set of openings, will always, when at rest, present one of these

imperforate portions to the points of the fingers 66. When in this position, with the boss 71 in its place, none of the selectors can make an engagement with any one of the bars operated by them, since at each forward vibration of the selectors 46 four of the finger-points 66 will rest on the imperforate portion of the stencil, while the fifth will strike the boss 71.

Upon the pivotal axis 45 is fulcrumed a lever, 74, one end of which lies just beneath the projecting end of the boss 71. The other or power end extends to a point near the rail of the embroidery-machine, and is perforated to receive a vertical bar, 75, mounted in any suitable supports by which it may have vertical movement. On this bar is a boss-nut, 76, overlying the end of the lever, and upon the upper end of the said bar is a cam-incline, 77, which lies beneath a tripping-point, 78, carried by the belt projection 4 of the needle-carriage. The purpose of this arrangement is as follows: The stitch adjustments of the tambour-frame must necessarily be initiated at the time when the retrograde movement of either needle-carriage has wholly withdrawn the needles from the web, and in order to make the automatic action complete it is requisite that the said movement should be timed by the said needle-carriages. This is therefore the function of the bar 34, actuated by the outer member of the series of selectors 46, the operative engagement of the latter with said bar being permitted by the recession of the carriage, which trips the lever 74 and throws the boss 71 upward, leaving an open space, within which the finger-point on the outer selector may enter. This having taken place, the selector raises the bar 34 with the upward movement of the platform, thereby raising the arm 38, lifting the latch 40, rocking the arm 56, by which the feed-pawl 57 is retracted, and thus causing the pitman 60 to throw said pawl forward and turn the feeding-disk 52. This advances the stencil-sheet a single step, removing its imperforate portion from over the openings 68 in the drum-sections 51, and bringing the end of one, or it may be two, of the openings b' b'' , &c., into position to expose the openings 68. At the next ensuing reciprocation of the platform the finger-points 66 of the proper selectors 46 enter the said openings, and an operative engagement being thus made between their selectors and the corresponding motor-bars, a' a'' , &c., the stitch adjustment of the tambour-frame is initiated. The first step movement of the feed-disk 52 brings the boss 71 back to its normal position, and thereby excludes the feed-finger from the opening in the drum, throwing the selector carrying said finger out of action. The successive feed movements of the stencil are, however, continued by the successive rise of the motor bar or bars called into action by the openings presented by the stencil.

The several racks on the slide-bars are so toothed and their actuating-pawls have such throw that at each reciprocation of the motor-

bar in action the tambour-frame is moved exactly the distance of a single stitch, which is equal to the thickness of the needle making the stitch. If a single movement only is required by the exigencies of the design, the stencil-opening is of such length as to permit but a single engagement between the selector and the motor-bar. Adjustment of greater length and requiring repeated action of the motor-bars will be provided for by increasing the length of the stencil-openings proportionately. The direction of the adjustment will be controlled by the relative transverse arrangement of these openings. As illustrated, the series *b'* of the stencil will control the downward movements of the pantograph-arm, the series *b'* the upward movements, and the remaining two series the right and left horizontal movements, respectively. Therefore, openings in the same transverse line can never be brought into adjacent series. It is unnecessary to explain that as the platform falls after each lift of the selectors the finger-points 66 are all withdrawn from the drum and stencil to permit the unimpeded feed movement of the latter between successive actions of the selectors.

In order to insure the exact action of the pawls 21 and 23, I mount upon any suitable support a steel plate, 79, upon which the nose of the pawl rides up as the bell-crank make their retractile vibrations. As the pawls are thrown forward, they ride off the plates and drop into the teeth of the racks, the plates being so located that after each step movement the next ensuing tooth shall lie in position to engage the pawl the instant it falls from the end of the plate. If desired, these plates may be made adjustable, so that the effective throw 40 of the pawl may be varied.

To provide against the risk of damage should the mechanism be accidentally started when the stencil is not on the drum, I mount on one of the lever-points a curved arm, 80, Fig. 4, 45 having upon its extremity a cam-plate, 81. The position of these parts is such that should both levers happen to act simultaneously the cam-plate 81 will engage a pin or stud, 82, on the pawl carried by the other lever and lift it 50 out of engagement with the rack. This arrangement might be duplicated upon the other lever also, and it is applied in like manner to the pawl-carrying levers 26 and 27, operating the vertical slide-bar 9.

55 The stencil-sheet herein described may be infinitely varied in the relative arrangement and length of its openings, whereby an infinite variety of designs may be worked out by the automatic adjustment of the tambour-frame, combined with the action of the embroidery mechanism proper. This stencil constitutes the directing power of the entire mechanism, and by the endless combinations of its four series of openings designs of the 60 utmost intricacy and beauty may be successfully and automatically worked out. The perfect accuracy of mechanical action as com-

pared with the work of the skilled operative, and especially with the work of different hands; or of the same hand at different times, 70 imparts a uniformity of appearance to the products of the machine which is readily distinguishable to the trained eye. Moreover, the simplicity of the mechanism, its positive action, and the exactness with which it works 75 out the designs represented by the stencil combine to render my invention superior in excellence of work, as well as in economic results, to any machine in which human agency 80 is the directing or controlling power.

In both my former applications mentioned herein I have shown a stencil for a purpose similar to that herein described. In these cases, however, the stencil controlled the stitch adjustment by the make and break of separate 85 electric circuits. I make no claim in the present case for this specific method of applying the stencil, nor for the several specific combinations in which it stands as an element in either of said applications.

It should be noted that the stencil forming part of my invention, whether it be constructed as shown in the accompanying drawings or in the manner last above mentioned, admits of but four effective series of openings 95 by which the vertical and horizontal adjustments are directed. All stitch adjustments in lines other than a vertical and horizontal are resultants of these two movements combined, whether acting separately or simultaneously. It must be remembered, also, that in preparing the stencil adjustments in opposite directions must invariably be effected by openings in different transverse series in the stencil. For example, the upward and downward movements cannot have coexistence 100 in the same series of openings, having regard to the transverse arrangement.

Any movements in lines at right angles to each other may be made simultaneously, and the openings representing and directing such adjustments may lie side by side in the stencil; but opposite adjustments must be governed by openings cut in successive transverse series, and this rule is without exception.

The operation of the machine is briefly as follows: The web being stretched upon the tambour-frame and the latter connected with the pantograph apparatus in the usual manner, the stencil 64 is carried over the drum 120 51 and stretched or in any way drawn down upon the drum, so that the teeth 53 engage with the central openings, 65, in the stencil. The needles being arranged in the jaws of one of the carriages and threaded, the mechanism 125 is ready for operation. The power-shaft being set in motion, rotation is imparted to the shaft 43, whereby a continuous rise and fall of the platform 42 is produced, together with the parts carried thereby. At the same time the shaft operating the railway is operated and presently one of the needle-carriages, having taken the needles after they are driven through the web, begins to recede from the 130

- tambour-frame. As the needles leave the fabric, the tripping-point 78 on the carriage drives down the bar 75, tripping the lever 74 and raising the boss 71. The selector beneath the bar 34 is then at liberty to rock under and make engagement with the said bar, its finger 66 entering the recess lately occupied by the boss 71. The bar 34 is thereby lifted, operating the latch 40 and initiating the movement 10 of the stencil-sheet, whereby the transverse imperforate portion moves off the openings 68 in the drum, causing one, or it may be two, of the openings b' , b^2 , b^3 , or b^4 to present themselves to the fingers 66 and uncover one, or possibly 15 two, of the openings 68. Upon the next lift of the platform the finger or fingers corresponding with the opening or openings presented to them pass into said openings, permitting the selectors to engage the motor-bars a' , a^2 , a^3 and 20 operate their levers, thus giving a single stitch adjustment to the tambour-frame. The platform now sinks, and the finger-points being retracted by the yoke 48, the pitman 60 advances the stencil-sheet 64 a single step, after which 25 the platform is again lifted. If the opening in the stencil continues to present itself to the same finger, the engagement of the selector and motor-bar is repeated and the adjustment of the tambour-frame is carried a single step farther, this being followed again by a progressive 30 movement of the stencil. This operation continues until an imperforate portion of the stencil presents itself to the fingers 66. This at once throws all the selectors out of action, 35 and consequently checks the advance of the stencil by the failure of the latch 40 to lift the horizontal bar 63 on the end of the vibrating pawl-carrier 56. The boss 71 having been restored to its normal position immediately after 40 the first lift of the bar 34, all operative engagement of any one of the selectors 46 is prevented until the next passage of the needle-carriage over the end of the tripping-lever 74. The latch 40 is pivoted on a boss, 83, projecting 45 from the standard 6, and the shaft 43 is mounted in a solid bearing, 84, on the standard 6; but these minor details of construction may be considerably varied, as circumstances 50 may require.
- 50 By the term "selectors" as used throughout this specification I refer to the pivotally-mounted fingers 46, which at each reciprocation seek to make engagement with the motor-arms 34, a' , a^2 , a^3 , and a^4 , such engagement being timed and controlled by the stencil. At 55 each advance of the latter said devices select from the motor-arms those which are required to act in order to give the necessary adjustment.
- 60 What I claim is—
1. In an embroidering-machine of the type described, an automatic mechanism for imparting the stitch adjustment to the tambour-frame, a stencil-sheet having four longitudinal 65 series of openings cut therein, and means for enabling said series of arms to time and control the two vertical and two horizontal adjust-

ments, respectively, and means for giving a stated progressive movement to said stencil-sheet, the four series of openings representing 70 the two vertical and two horizontal adjustments of the tambour-frame, substantially as specified.

2. In an embroidering-machine, the combination, with the tambour-frame, of a pantograph, independent slide-bars connected with 75 the motor-arm of the pantograph and having vertical and horizontal adjustment, respectively, a stencil-sheet having four longitudinal series of openings, which time and control 80 said adjustments, and automatic devices intermediate of said stencil and the slide-bars and effecting the adjustments of the latter, substantially as specified.

3. In an embroidering-machine having a 85 tambour-frame and a pantograph apparatus connected therewith, the combination, with the motor-arm of the pantograph, of vertically and horizontally moving devices, reciprocating feeders having engagement with said devices, 90 selectors adapted to operate said feeders, and a stencil-sheet having four separate longitudinal series of openings for timing and controlling the stitch adjustment, substantially as specified. 95

4. In an embroidering-machine, the combination, with devices for adjusting the tambour-frame, of independent adjusting devices communicating vertical and horizontal movement to the tambour-frame, a stencil-sheet having 100 four longitudinal series of openings for timing and controlling the two vertical and two horizontal movements of the adjusting devices, and means for giving a progressive movement to the stencil, substantially as specified. 105

5. In an embroidering-machine, the combination, with an intermittently-advancing stencil-sheet, of reciprocating selectors and vertically and horizontally moving adjusting devices connected to the apparatus which supports the tambour-frame, said selectors imparting their reciprocatory movement at stated intervals to the adjusting devices, the stencil-sheet being provided with four longitudinal 110 series of openings for timing and controlling 115 the stitch adjustment, said openings representing the two vertical and the two horizontal 120 adjustments therein, substantially as specified.

6. In an embroidering-machine, the combination, with the tambour-frame and a pantograph apparatus connected therewith, of adjusting devices connected to the motor-arm of the pantograph and having independent vertical and horizontal adjustment, selecting and 125 actuating devices having continuous reciprocatory movement, a stencil-sheet having four series of openings representing the two vertical and two horizontal adjustments, means for giving a progressive advancement to the stencil-sheet, and independent mechanism for initiating the stitch adjustment at proper times 130 with relation to the action of the needle-carriages, substantially as specified.

7. In an embroidering-machine, the combination, with the tambour-frame and a pantograph apparatus giving adjustment thereto, of independent arms having cruciform arrangement, slide-bars carrying said arms, reciprocatory devices giving adjustment in two vertical and two horizontal directions to said slide-bars, selectors having continuous reciprocation and means to cause said selectors to engage at stated intervals with the adjusting devices, a stencil-sheet having four series of openings of varied length and arrangement representing the two vertical and two horizontal adjustments of the tambour-frame, and means for advancing said stencil intermittently, the cross-arms having independent connection with the end of the motor-arm of the pantograph, substantially as specified. 5
8. In an embroidering machine, the combination, with the stitch-adjusting mechanism, of a stencil-sheet having four series of openings of varied length and arrangement representing the two vertical and two horizontal adjustments of the tambour-frame, a rotating feed-disk advancing said stencil, a vibrating pawl-carrier moving a ratchet on the shaft of said disk, a pitman throwing the pawl-carrier in one direction, and a latch operated by the stitch-adjusting mechanism and retracting the pawl to give an advance movement to the stencil, substantially as specified. 10
9. In an embroidering-machine, the combination, with the tambour-frame and a pantograph apparatus connected therewith, of slotted arms having cruciform arrangement, reciprocatory pawl-carriers acting upon opposite racks on each arm, motor-bars actuating the pawl-carriers, continuously-vibrating selectors, means for causing said selectors to engage at stated intervals with one or more of said motor-bars, and an intermittently-advancing stencil-sheet having four series of openings, which time and control the action of said selectors, the motor-arm of the pantograph having an independent connection with each of the slotted cross arms, substantially as specified. 15
10. In an embroidering-machine, the combination, with the tambour-frame and adjustable supports connected therewith, of independent arms having connection with the adjustable supports of the tambour-frame, and reciprocatory pawl-carriers acting upon double racks carried by said arms and giving them a vertical and a horizontal movement alternately or simultaneously, motor-bars actuating said pawl-carriers, selectors having continuous vibration and means for causing said selectors to engage at stated intervals with said motor-bars, a stencil having progressive movement and provided with four series of openings which represent the two adjustments of the tambour-frame, and means for advancing said stencil synchronously with the presentation of any one or more of the stencil-openings to the selectors, substantially as specified. 20
11. In an embroidering-machine, the combination, with the tambour-frame and with supports therefor having two vertical and two horizontal adjustments, of a stencil-sheet having four series of openings representing by their relative longitudinal and transverse arrangement the relative time and direction, respectively, of the several stitch adjustments, and mechanism directed and controlled by said stencil for effecting said adjustments, the degree of movement being represented by the length of the stencil-openings, substantially as specified. 25
12. In an embroidering-machine, the combination, with the tambour-frame and with supports therefor which are capable of the movement required for the stitch adjustment, of a stencil having four series of openings representing by their relative longitudinal and transverse arrangement the relative time and direction, respectively, of the successive stitch movements, automatic mechanism controlled by said stencil for effecting said movements, means for advancing the stencil, and a timing apparatus whereby the stitch movement is made to alternate with the action of the stitch-forming mechanism, substantially as specified. 30
13. In an embroidering-machine, the combination, with the tambour-frame, the adjustable supports therefor, and means for effecting the stitch movements to said supports, of a stencil having four series of openings which control the successive stitch movements of said frame, the relative longitudinal and transverse arrangement of said openings determining the time and direction of said movements, opposite vertical and horizontal movements being represented by openings in different transverse series, while the combined vertical and horizontal movements may be controlled by openings in the same transverse series, substantially as specified. 35
14. In an embroidering-machine, the combination, with the tambour-frame and supports therefor capable of the adjustment required to admit of the stitch movements, of a stencil governing the mechanism by which said movements are effected, a feed mechanism for said stencil, and a timing device actuated by the stitch-forming mechanism, whereby the effective or operative selections of the stencil alternate with the action of said mechanism, substantially as specified. 40
15. In an embroidering-machine, the combination, with the supports sustaining the tambour-frame, of automatic mechanism effecting the stitch movements, said mechanism consisting of a stencil having openings representing the relative time, direction, and length of the several movements successively, four continuously-moving selectors by which the two vertical and two horizontal movements of the tambour-frame are effected, means for advancing the stencil, a fifth selector by which said advance movement is initiated, and a timing lever actuated by the needle-carrying apparatus, by which said selector is permitted to act, substantially as specified. 45

16. In an embroidering-machine, the combination, with a stencil which controls the automatic stitch movement, of a feed for said stencil, a vibrating pawl-carrier having a swiveling eye or sleeve, a pitman running loosely in said eye and having a nut or boss which vibrates the pawl-carrier in one direction only, and a vibrating arm which retracts the pawl after each stroke, said arm having connection with the stitch-adjusting mechanism, whereby the advance of the stencil is rendered synchronous with the continued presentment of one or more of its openings and alternates with the action of the needles, substantially as specified.

17. In an embroidering-machine, the combination, with a vibrating platform, of selecting devices pivotally mounted thereon, springs impelling said devices to rock in one direction, a rigid yoke rocking them as the platform drops to or near its limit of movement in the opposite direction, a stencil having four series of openings which govern the adjustments of the tambour-frame, a drum over which said stencil is fed, a feeding-pawl retracted after each stroke by the effective action of one or more of said selecting devices, an independent device by which the initial retraction is given, and a timing device by which the independent selector giving it is brought into action for a single stroke to initiate the advance of the stencil, substantially as specified.

18. In an embroidering-machine, the combination, with a tambour-frame and its supports, of two independent arms or bars acting the one in a horizontal and the other in a vertical direction, vibratory levers carrying pawls which are normally impelled to engage with racks on said arms or bars, selecting devices having continuous reciprocation, a stencil having four series of openings representing the two vertical and two horizontal movements of said arms or bars, and means for feeding said stencil and for causing said selectors to vibrate toward and from the same between their successive reciprocations, substantially as specified.

19. In an embroidering-machine, the combination, with the tambour-frame and the stitch-forming mechanism, of an automatic stitch adjustment consisting of arms or bars acting in lines at right angles to each other, said arms having each a double rack with the teeth pitched in opposite directions, vibrating pawl-carriers having spring-impelled pawls engaging with said racks, continuously-reciprocating selectors acting upon the pawl-carriers, a stencil bringing said selectors into and out of action, said stencil having openings representing by four different series the two vertical and two horizontal adjustments of the tambour-frame, and means for repeating individual adjustments as often as the openings require, the opposite movements in the same plane being effected by different transverse series of openings, substantially as specified.

20. In an embroidering-machine, the combi-

nation, with arms or bars having oppositely-toothed racks, of pawl-carriers having spring-impelled pawls engaging said racks, relief-plates underlying said pawls and intermediate between the same and the racks, and an arm rigid on one of said pawl-carriers and provided with a cam-incline engaging with a pin on the nose of the pawl carried by the opposite lever when both pawl-carriers vibrate simultaneously, substantially as specified.

21. In an embroidering-machine, the combination, with the devices whereby the successive stitch movements are imparted to the tambour-frame, of a directing or controlling mechanism consisting of a stencil having four series of openings representing the time, direction, and length of the several stitch movements, five independent selectors having continuous reciprocation and an intermediate vibration on a pivotal axis toward and from the stencil, a corresponding series of bars arranged to have engagement at the intervals designated by the stencil with the selectors, an arm raised by the lift of any one of said bars, a feed-pawl retracted by the rise of said arm, a pitman throwing the feed-pawl forward only, and a timing-lever by which a single effective action of the fifth selector is permitted to initiate the advance movement of the stencil, substantially as specified.

22. In an embroidering-machine, the combination, with the tambour-frame and the stitch-adjusting supports, of a directing or controlling mechanism consisting of a vibrating support, a series of selectors pivotally mounted thereon, an intermittently-advancing stencil having four series of openings which control the direction, extent, and time of the successive stitch movements, a pawl-and-ratchet feed for the stencil, the effective throw of the pawl being by the stroke of a pitman, and a vibratory latch-bar raised by the effective lift of any one of the selectors and by its rise re-tacting the pawl-carrier for initiating the feed movement of the stencil and continuing it to the extent required by the length of opening, substantially as specified.

23. In an embroidering-machine, the combination, with the movable or actuating member of a pantograph, of independently-connected arms or levers acting the one in a vertical and the other in a horizontal direction, reciprocatory feeders engaging with and moving said arms a step at each reciprocation, a series of continuously-reciprocating and intermediately-vibrating selecting devices carrying fingers which are supported and projected forward at each vibration, a stencil having openings which represent the time and direction of the movements of the said arms or bars, a pawl-and-ratchet feed for the stencil, and devices for actuating said feed, said devices being in part operated by the effective lift of any one or more of the selectors and in part by the throw of the pitman, substantially as specified.

24. In an automatic stitch-adjusting mech-

anism for an embroidering-machine, a drum-support for a controlling-stencil, a feed-disk having teeth engaging said stencil, said disk turning between the separate drum-sections, a 5 ratchet on the shaft of the disk, a pawl-carrier vibrating on the end of said shaft, a spring-impelled pawl engaging the ratchet, a pitman reciprocating in a support swiveled on the pawl-carrier and vibrating the latter one way, to a latch vibrating it in the opposite direction, and a series of bars which have independent connection with the said latch, which rises by

the lift of any one or more of said bars, four of said bars having action upon the stitch-adjusting devices, and the fifth having as its 15 sole function to initiate the advance of the stencil, substantially as specified.

In testimony whereof I affix my signature in presence of two witnesses.

ROSWELL T. SMITH.
